DESIGN FOR A PLATE FOR HEAT EXCHANGER

Charles Brown Dalzell, Little Falls, N. Y., assignor to Cherry-Burrell Corporation, Wilmington, Del., a corporation

Application October 1, 1938, Serial No. 80,165

Term of patent 14 years

To all whom it may concern:

Be it known that I, Charles Brown Dalzell, a citizen of the United States, residing at Little Falls, in the county of Herkimer and State of New York, have invented a new, original, and ornamental Design for a Plate for Heat Exchanger, of which the following is a specification, reference being had to the accompanying drawing, forming part thereof.

In the drawing:

Fig. 1 is a plan view of the plate for heat exchanger showing my new design;

Fig. 2 is a sectional view of the plate for heat exchanger taken along lines 2—2 of Fig. 1.

I claim:

The ornamental design for a plate for heat exchanger, substantially as shown.

CHARLES B. DALZELL.
